T. M. PRIM

AUTOMATIC RAILROAD SWITCH

Filed Sept. 26, 1922

By

R. W. Hoagland

Attorney

UNITED STATES PATENT OFFICE.

THOMAS M. PRIM, OF ONTARIO, CALIFORNIA.

AUTOMATIC RAILROAD SWITCH.

Application filed September 26, 1922. Serial No. 590,691.

To all whom it may concern:

Be it known that I, THOMAS M. PRIM, a citizen of the United States, residing at Ontario, in the county of San Bernardino, 5 California, have invented a new and useful Automatic Railroad Switch, of which the following is a specification.

My invention relates to certain new and useful improvements in switches, constructed 10 so as to direct rolling stock in one direction, while allowing it to return from more than one direction.

An important object of the invention is the provision of a switch to direct rolling 15 stock in one direction and also of means for shifting the switch when returning from another direction without the wheels actually striking the shifting rails.

A further object is to construct switches 20 of such a nature that two cars traveling in opposite directions upon a single straightway track will be switched to turnout tracks and back onto the straightway track for passing one another without the necessity of 25 manually operating the switches.

A still further object of the invention is to provide means for manually operating the switch, so as to direct rolling stock in either direction.

30 Other objects and advantages of the invention will be apparent during the course of the following description.

In the accompanying drawings forming a part of this specification and in which like 35 numerals are employed to designate like parts throughout the same;

Figure 1 is a diagram showing my improved switches in use.

Figure 2 is an enlarged plan view of one 40 switch.

Figure 3 is a perspective view of the movable switch body, and

Figure 4 is a section taken on line 4—4 of 45 Figure 2, showing the switch being thrown.

Referring to the drawing, A and B indicate the straightway tracks, while C and D designate the turnout or passage track portions. Where the tracks C and D terminate at the two straightway tracks A and B are 50 provided the two switches E and F. Said switches are so constructed that the rolling stock coming off of either straightway track A or B will turn to the right. Thus the rolling stock coming from straightway track 55 A will be guided upon the turnout or passage track D, while from B the rolling stock

will be directed on turnout or passage track C. Upon track D is provided another switch G to be manually operated for directing the rolling stock onto the side track H. Said 60 side track is used for dropping freight cars and the like.

Referring to the switches E, F and G, the numerals 10 designates a movable body having the track portions 11 and 12 thereupon 65 adapted to be moved from one rail of the straightway track to the other, as the body is swung upon a pivot as at 13. Said track portions 11 and 12 are tapered and terminate in sharp edges at the outer ends, while the 70 inner ends are cut at right angles as at 14 and 15 so that they will form continuations of the inner rails of track portions C and D, and align therewith. Suitable guard rails 16 are connected to the sides and at the terminals of the inner rails of the tracks C and D and extend back a short distance and are parallel with the outer rails of said track portions C and D.

At one end of the body 10 extends an arm 80 17 having a beveled face on one side, as at 18. The lower surface of the arm 17 is cut away as at 19, to allow said arm to overlap the rail. The other side of said arm 17 also has its lower portion cut away as at 20 to 85 also allow said arm to extend over a rail when the switch is thrown.

A cutout portion 21 is provided in the body 10 to receive the head of a bolt 22, in order that said bolt may be carried by said 90 body 10. The bolt 22 extends through one of the rails of tracks C and D and has a coiled spring 23 on its outer end so as to yieldably hold said body 10 against one of the rails of the straightway tracks. Suitable means is provided as at 24, for adjusting the tension of said spring 23.

As indicated at 25, an arm 26 is pivotally secured for manually shifting the body 10 upon its pivot 13 against the tension of the 100 spring 23. Cut out portions such as shown at 27 and 28 may be provided in order to lighten the weight of the main body 10.

In the operation of the device, when rolling stock enters by way of straightway track A, it will turn to the right and be directed upon turnout or passage track D as the movable body 10 of the switch E is held in the position as shown in the drawing by means of spring 23, while another rolling 105 stock entering upon straightway track B will be turned to the right and directed upon 110

turnout or passage track C, as indicated in the drawings. As the rolling stock or cars keep moving, the wheels on one side of such stock will strike the beveled face 18 of arm 17 and shift the rail portions 11 and 12 to the other side against the tension of the spring 23, thus allowing the rolling stock to enter upon the straightway tracks again. It will thus be seen that two separate cars 10 traveling in opposite directions can pass without the manual operation of a switch.

To enter the side track H it is necessary to manually operate the switch G, while returning out upon the main tracks the switch 15 will be operated by the wheels of the rolling stock, as hereinbefore described.

Another switch such as G can be applied at the outer end of the side track H so as to allow rolling stock to enter upon the side 20 track H and drop off cars and move straight ahead and out on the main track again.

It is to be understood that the forms of my invention herewith shown and described, are to be taken as preferred examples of the 25 same, and that various changes in the shape, size, and arrangements of parts may be resorted to without departing from the spirit of the invention or the scope of the subjoined claims.

Having thus described my invention, I 30 claim:

1. A switch of the character described, comprising a movable switch member, an arm extending forwardly from said switch member to be operated by the wheels of rolling stock for shifting the switch member, and spring means for returning said switch member to normal position.

2. A switch of the character described, 40 comprising a pivoted switch body, a pair of rails rigidly secured upon said body, and an arm rigidly secured to and extending from the end of said body to be operated by the wheels of rolling stock for shifting the body portion carrying said rails.

3. A switch of the character described, 45 comprising a switch body pivoted at one end, a pair of rails carried by said body, and an arm rigidly secured to and extending forwardly from the pivoted end of said body to be operated by the wheels of rolling stock for shifting said body carrying the said switch rails.

4. A switch of the character described, 55 comprising a pivoted switch body, rails carried by said body, and an arm extending forwardly from said body to be operated by the wheels of rolling stock for shifting the body carrying said switch rails, and spring means for returning said body to normal position.

5. In a switch, the combination with a 60 straightway track and turnout tracks diverging from said straightway track, of a movable switch body for directing rolling

stock upon a certain one of said turnout tracks, and an arm extending forwardly from said body adapted to engage the wheels of rolling stock for moving said switch body upon returning to the straightway track 70 from the other of said turnout tracks.

6. A switch of the character described, comprising a pivoted switch body, rails carried by said body, and an arm extending forwardly from said body to be operated by 75 the wheels of rolling stock for shifting the body carrying said switch rails, spring means for returning said body to normal position, and means for manually operating said switch.

7. A switch of the character described, comprising a switch body pivoted near one end, rails carried by said body, an arm extending from the pivoted end of said body to be operated by the wheels of rolling stock 85 for shifting the body portion carrying said rails in a direction opposite to the movement of said arms, a rod extending from said body, and a coil spring about said rod for returning said body to normal position. 90

8. In a switch, the combination with a straightway track and turnout tracks diverging from said straightway track, of a movable switch body, and an arm extending forwardly from said body and adjacent one 95 of the rails of one of the turnout tracks adapted to be moved by the wheels of rolling stock upon said rail, said arm being cut away on its lower surface to allow the end of said arm to overlap said rail to give 100 a greater throw of said switch body.

9. In a switch, the combination with a straightway track, turnout tracks diverging from said straightway track, the inner rails of said turnout tracks terminating a short 105 distance from said straightway tracks, of a pivoted switch body, short rails carried by said body adapted to align with said rail terminations, and an arm extending forwardly from said body adapted to be operated by rolling stock wheels for shifting said body carrying said short rails from one of the rails of said straightway track to the other rail.

10. In a switch, the combination with a straightway track, and turnout tracks diverging from each other and from said straightway track, of a pivoted switch body, short rails upon said body, an arm extending from said body and adjacent one rail of one of the turnout tracks, and spring means adapted to yieldably hold one of the short rails carried by said body against one of the rails of said straightway track, for directing rolling stock upon one of the turnout tracks, while rolling stock can return upon the other turnout track by the wheels thereof engaging said arm to move the rails carried by said body.

THOMAS M. PRIM
